UNITED STATES PATENT OFFICE.

HENRY J. WIEGAND, OF MILWAUKEE, WISCONSIN, ASSIGNOR TO THE CUTLER-HAMMER MFG. CO., OF MILWAUKEE, WISCONSIN, A CORPORATION OF WISCONSIN.

RHEOSTAT.

1,130,949.

Specification of Letters Patent.

Patented Mar. 9, 1915.

Application filed August 2, 1912. Serial No. 712,929.

To all whom it may concern:

Be it known that I, HENRY J. WIEGAND, a citizen of the United States, residing at Milwaukee, in the county of Milwaukee and State of Wisconsin, have invented new and useful Improvements in Rheostats, of which the following is a full, clear, concise, and exact description, reference being had to the accompanying drawing, forming a part of this specification.

My invention relates to improvements in rheostats. It is particularly applicable to rheostats of the disk type but includes features applicable to other types of rheostats.

The various objects and advantages of my invention will be hereinafter set forth.

For the purpose of clearly and fully disclosing the nature and advantages of my invention I shall describe the embodiment thereof illustrated in the accompanying drawing, it being understood that my invention is susceptible of modification.

In the drawing, Figure 1 is a side elevation of the device. Fig. 2 is a front elevation of Fig. 1, and Fig. 3 is a detail sectional view.

The rheostat selected for the purpose of illustration is one of the disk type, particularly applicable to theater dimmers. It comprises an insulating circular base 1, preferably of soap-stone, in which is embedded a resistance not shown and a circular series of contacts 2 connected to the resistance. It has a duplex lever 3 movable over the contacts 2 to vary the resistance. It has heretofore been proposed to provide rheostats of this and similar character with metallic casings to protect the same and to facilitate the mounting thereof upon a suitable supporting base or frame. Such casings, however, are open to numerous objections, among which may be mentioned the expense thereof, the space occupied thereby and the difficulty of firmly securing the rheostat base therein. Of course, where the rheostat base is circular it must not only be secured within the casing but must be locked against rotary slippage. The necessity for such casings is entirely eliminated in the rheostat shown in which a peripheral band 4 serves all of the purposes of the casing and also other purposes. The band 4 is preferably formed in two parts *a* and *b* of substantially the same size although in practice the same may be

formed in any number of sections and the sections may be of any preferred size. Each of the sections *a* and *b* is provided at opposite ends with radial lugs or ears 5 and 6. Bolts 7 and 8 pass through the lugs of one section and thread into the lugs of the other section, thereby providing a very simple means for drawing the sections together to tightly clamp the same on the rheostat base. The band may in practice merely comprise a flat strip but I prefer to provide the band with annular flanges 9 (Figs. 1 and 3) to engage the opposite faces of the rheostat base thus insuring against lateral displacement of said band. Further, I preferably bevel the edges of the base 1 as indicated at 10 and provide the flanges 9 of the band with converging inner faces 9^a engaging said beveled edges of the base. This insures a tight grip of the band on the base by wedging action. Where the rheostat is provided with peripheral terminals, such as the terminals 11 and 12 illustrated, I prefer to provide the band with a peripheral opening 13 to receive said terminals and to widen the flanges 9 and 10 at the sides of this opening, as shown at 10^a. The widened flanges reinforce the band contiguous to the opening. The band is preferably metallic and rigid.

It will be observed that when the band 4 is clamped onto the rheostat it reinforces, strengthens and protects the same. It will further be observed that the band becomes an integral part of the rheostat and that the structure as a whole occupies only a very slightly greater space than the base itself. Still further, it will be observed that the band forms a very convenient means for attaching the rheostat to a suitable frame or other form of support.

The supporting frame shown is of a type particularly adapted for theater dimmers and designed to carry a plurality of rheostats side by side. It comprises L-shaped end members 15 having cross bars 16, 17 and 18, two at the back and one at the bottom of the frame. Where the rheostat is to be mounted upon such a frame the band 4 is preferably provided with peripheral lugs 19, 20 and 21, each having a laterally extending ear 22. The ears of the lugs 19, 20 and 21 are secured by screws 23 to the cross bars 16, 17 and 18 respectively of the supporting frame. Of course, in practice the

band might be secured to the supporting frame in various other ways.

A dowel pin 24 is preferably provided on the band to project into a recess in the rheostat base to insure the desired circumferential relation between the band and the base. However, various other means might be provided for this purpose.

Having thus described my invention what I claim as new and desire to secure by Letters Patent is:

1. A rheostat provided with a rigid flat base for carrying the electrical parts, and a supporting band extending around said base and interlocked therewith to prevent slippage thereon.

2. A rheostat provided with a rigid flat circular base for carrying the electrical parts and a reinforcing and supporting band extending around the periphery of said base, said band being clamped to said base and positively secured against lateral displacement.

3. A rheostat provided with a flat base and a band surrounding the same and clamped thereto, said band having side flanges on opposite sides of said base.

4. A rheostat provided with a circular

base and a peripheral band clamped thereto, said band being provided with annular side flanges.

5. A rheostat provided with a circular base and a peripheral band clamped thereto, said band being provided with annular side flanges, and peripheral supporting lugs.

6. A rheostat provided with a circular base having terminals on the periphery thereof and a peripheral reinforcing and supporting band clamped to said base, said band having an opening to receive said terminals and annular side flanges, said side flanges being of increased dimensions contiguous to said opening.

7. The combination with a rheostat having a rigid flat base for carrying the electrical parts, of a supporting frame therefor, and a clamping band surrounding said base and secured to said frame in a perpendicular relation thereto.

In witness whereof, I have hereunto subscribed my name in the presence of two witnesses.

HENRY J. WIEGAND.
